TRAIN DISPATCHING SYSTEM FOR RAILROADS

Frank Benedict, Rutherford, N. J., assignor to General Railway Signal Company, Rochester, N. Y.

Application March 8, 1928, Serial No. 260,178

16 Claims. (Cl. 246—3)

This invention relates to train dispatching systems of the wayside signal indicating type.

In a train dispatching system in which the movement of the train is dispatched through the medium of semiautomatically controlled signals, located either in the cab or along the wayside, not only is it necessary to superimpose manual control upon these signals from a central point, such as a dispatcher's office, but it is also necessary to indicate at the tower the location of trains along the track and their progress. It readily appears that if a single operator or dispatcher is to dispatch the movements of trains over an appreciable stretch of track, such as 100 miles, a large number of distinctive controls must be available to him, and further provision must be made for transmitting a large number of distinctive OS indications. The present invention deals more particularly to control and indicating means in which a large number of distinctive controls and a large number of distinctive indications may be transmitted over a single line circuit. In order to indicate the location and progress of trains it is proposed to indicate at the dispatcher's office the condition of occupancy of track circuits along the railway track. It is of course understood that not only is it possible for two or more track circuits to become occupied or unoccupied at exactly the same time, but this is something that is very likely to happen and may even be a daily occurrence; and since, in accordance with the present invention, it is proposed to transmit distinctive signal indications by distinctive codes it is essential that two codes should not be transmitted over the same line circuit simultaneously, for if this were possible the resulting code might give a false indication, or constitute a jumbled code which would give no indication at all.

With the foregoing and other important considerations in mind it is proposed in accordance with the present invention to provide distinctive code responsive relays at both the dispatcher's office and at each way station, and to transmit distinctive codes from and to these various way stations to operate such code responsive relays. More specifically, it is proposed to provide manually operable calling keys at the dispatcher's office to operate the code responsive relays at the way stations, to provide automatically operated calling keys or code transmitters at the way stations for transmitting codes to the code responsive relays located in the dispatcher's office, and to provide suitable lockout means whereby it is impossible for two code transmitters to transmit

a code over the coding circuit simultaneously. In the specific embodiment of this lockout means it comprises a normally de-energized lockout circuit having lockout relays and secondary lockout relays associated therewith, the circuit arrangement being such that if a particular way station is to transmit a code to the dispatcher's office the lockout circuit portion beyond that particular way station is cut off by opening the circuit at that point, and the portion of the lockout circuit between the dispatcher's office and this particular way station is energized, provision being made to lock out a way station if the lock out circuit is energized from another way station.

Other objects, purposes and characteristic features of the present invention are in part obvious from the accompanying drawings and will in part appear from the description hereinafter.

In describing the invention in detail references may be had to the accompanying single drawing contained on two separate sheets which may be laid end to end, and of which:

Fig. 1A shows conventionally the apparatus located in the dispatcher's office, together with part of the trackway means; and

Fig. 1B shows a passing siding of a railway system, of which the switch machines and signals are controlled by distinctive codes in accordance with the present invention, and in which the presence of a train on the detector track circuits associated with this passing siding is indicated at the dispatcher's office in accordance with the present invention.

Apparatus at dispatcher's office

In the dispatcher's office, conventionally illustrated by the rectangle DO, is preferably provided a suitable train dispatching machine having associated therewith a miniature track layout of which the passing siding PS¹ has been shown, this passing siding is to represent the passing siding PS¹ of the railway system shown in Fig. 1B of the drawings. At the west end of this passing siding PS¹ are shown a red lamp R² and a green lamp G², which if illuminated indicate the occupancy and if not illuminated unoccupancy, respectively, of the detector track circuit located at the west end of the passing siding PS¹. Associated with these lamps or indicators R² and G² is a lever L² whereby three different calling keys RC², CC², and NC² may be operated, each of these calling keys transmitting a distinctive code if operated. The lever L² is directly connected to the cancelling code calling key CC², whereby the cancelling code is

transmitted if the lever L^2 is moved in either direction through a certain angle from the normal position, and upon further movement of the lever the normal code or the reverse code is 5 transmitted, depending upon whether the lever is moved in the clockwise or the counterclockwise direction. When the lever is returned from one extreme position back to its normal neutral position, in which it is shown, the normal 10 or reverse code key NC^2 or RC^2 are not operated, but the cancelling code key CC^2 is operated, so that a cancelling code is transmitted. The normal code key NC^2 or the reverse code key RC^2 are not operated when the lever L^2 is returned 15 from the corresponding extreme position to the neutral position, because these keys are operated through the sectors 10, pinions 11, pawl 12 and ratchet tooth 13, and upon the return movement of the lever the pawl 12 merely disengages the 20 tooth 13.

It readily appears that if the lever L^2 is moved toward the right it may be moved a certain distance before it engages the projection 15 on the sector 10, after which the sector 10 moves with 25 the lever L^2 and rotates the pinion 11 and in turn the ratchet tooth 13 in a counterclockwise direction carrying the normal code key NC^2 with it, and that when the lever L^2 has been moved to a point where the sector 10 engages the stop 30 16 the normal code key NC^2 has been operated through exactly one revolution. If now, the lever L^2 is returned to its intermediate or neutral position the sector 10, pinion 11 and ratchet tooth 13 moves entirely without operating the 35 normal code key NC^2 . The reverse code key RC^2 is operated in exactly the same way upon movement of the lever L^2 in the counterclockwise direction and for this reason like parts have been assigned like reference characters, and for the 40 same reason like parts for operating the keys RC^3 , CC^3 and NC^3 by the lever L^3 have been designated by like reference characters.

For each lever in the dispatcher's office there 45 are also provided two code responsive relays CRR , a red indicating relay RI and a green indicating relay GI , and the dispatcher's office equipment also includes a repeater code relay RCR , a lockout relay LRS , a secondary lockout relay SLR and a master relay MR . The exact purpose 50 and function of these devices may readily be obtained from the operation of the system hereinafter described.

Way station apparatus

55 In describing the way station apparatus it is deemed sufficient to describe the apparatus associated with the east end of the passing siding PS^1 , and for convenience the apparatus associated 60 with the west end of this passing siding will be assigned like reference characters having distinctive exponents. This east end of the passing siding PS^1 includes the usual track switch S^3 , which track switch may be operated by the power operated switch machine SM^3 . The following portion of the track switch S^3 is provided 65 with the usual detector track circuit including the track relay DT^3 and the track battery 20, this detector track circuit being confined by the insulating joints 21. Although the wayside signals, which may be of any suitable construction, but which have been conventionally shown as comprising semaphore signals, may be semi- 70 automatically controlled and in accordance with traffic conditions in advance thereof in any suit-

able way as practiced in both double track and single track signaling, these signals are preferably controlled in a manner as shown in the application of S. N. Wight, Ser. No. 48,553 filed August 6, 1925, or if light signals are used they 5 are preferably controlled as shown in the application of S. N. Wight, Serial No. 120,423 filed July 3, 1926.

In the particular embodiment of the invention illustrated the entrance signal 1, take siding signal 1^d, starting signal 2 and the dwarf starting signal 2^d are controlled in accordance with the position of the track switch S^3 either through switch box contact or contacts associated with the switch machine SM^3 and the position of the 15 normal relay NR^3 and the reverse relay RR^3 , as more particularly described hereinafter. The starting signals 7 and 7^d and the entering signals 8 and 8^d at the west end of the passing siding PS^1 are controlled in the same way. The normal 20 relay NR^3 and the reverse relay RR^3 are controlled in accordance with distinctive codes transmitted to the code responsive relay CRR^3 all as pointed out in the operation hereinafter.

In order to indicate the occupancy of the detector track circuit containing the detector track relay DT^3 by the illumination of the green lamp G^3 or the red lamp R^3 in the dispatcher's office, a suitable code transmitter or automatical calling key CT^3 is provided at this way station. This 25 code transmitter is automatically controlled and is operated by the motor M , includes a code wheel comprising an occupied sector OC and an unoccupied sector UC , a pick-up cam PC^3 , a stop cam SC^3 , and isolating cam IC^3 .

This code transmitter CT^3 is operated in accordance with the conditions of the lockout or cut-out relay LR^3 the coding stick relay CSR^3 and the secondary lock relay SLR^3 . The manner in which these relays LR^3 , SLR^3 and CSR^3 40 may control the code transmitter CT^3 , and how these relays may prevent any other code transmitter being operated is most readily understood from the description of the operation of the system.

OPERATION

Dispatcher's control over switch machines and signals

Let us assume that there is an east bound (left to right) train moving in the single track section N , and that the dispatcher wishes to clear the signal 8 to permit this train to enter the main track of the passing siding PS^1 . In order to do so the dispatcher will move the lever L^2 toward the right, and during the first part of the stroke of the lever will operate the canceling key CC^2 , thereby transmitting a code which will cause the normally closed contact 25 of the code responsive relay CRR^2 to be momentarily opened. Operation of the canceling code key CC^2 causes the following circuit to be completed in interrupted fashion:—starting at the terminal B of a suitable battery, wire 26, back contact 27 of the secondary lockout relay SLR in the dispatcher's office, wire 28, indicating lamp 29, wires 30 and 31, canceling key CC^2 , wires 32, 33, 34 and 35, winding of the repeater code relay RCR and lockout relay LRS in multiple, to the terminal N connected to the other side of said battery.

It is obvious from the drawings that the relays RCR and LRS are connected in multiple in this same circuit. The lockout relay LRS is slow dropping as conventionally shown in the drawings, and this relay LRS keeps its contacts in the at- 75

tracted position continuously in spite of the interrupted closure of the circuit just traced. The repeater code relay RCR however is quick acting and causes its contacts 36 and 37 to close in code like fashion. With the slow acting lockout relay LRS energized, and the contacts 36 and 37 operated to simulate the cancelling code, the contact 25 of the code responsive relay CRR² is momentarily opened by reason of the interrupted energization of this code responsive relay CRR² to simulate the proper code through the following circuit:—beginning at the terminal B of a suitable battery, front contact 36 of relay RCR, wires 40, 41 and 42, front contact 43 of the lockout relay LRS, wire 44, back contact 45 of the secondary lockout relay SLR, coding wire WC, wire 46, back contact 47 of the secondary lockout relay SLR², wire 48, winding of the code responsive relay CRR², wire 49 to the common return wire C, through front contact 37 of the repeater code relay RCR to the negative terminal N of the same battery. This momentary opening of contact 25 of the code responsive relay CRR² assures the de-energization of the relays NR² and RR² in response to the transmission of the cancelling code.

If the lever L² is continued through its movement to the right it engages the projection 15 on sector 10 and operates the normal code key NC² through its entire revolution, thereby transmitting a distinctive code to all of the various code responsive relays. This distinctive code will, however, only momentarily close the contact 50 of the code responsive relay CRR². Momentary closure of the contact 50 closes a pick-up circuit for the relay NR², including the wires 51, 52 and 53, thereby picking up the relay NR², which thereafter is stuck up through the following circuit:—beginning at the terminal B of a suitable battery normally closed contact 25 of the code responsive relay CRR², wires 54 and 55, stick contact 56 of the relay NR², wires 57 and 52, winding of the relay NR², wire 53 to the negative terminal N of this battery.

With the normal relay NR² in its energized condition current may flow to maintain the signal 8 clear through the following circuit:—beginning at the terminal B of a suitable battery, wires 69 and 61, back contact 62 of the reverse relay RR², wires 63, front contacts 64 of the relay NR², wires 65 and 66, contacts 67—68, wires 69 and 70, mechanism of the signal 8, wires 71 and 72, through a front and polar contact of a suitable home relay (not shown), to the negative terminal N connected to the other side of said battery. The flow of current in this circuit will maintain the signal 8 clear providing traffic conditions in advance thereof are and remain favorable. It should be noted that the energization of the relay NR² did not effect operation of the switch machine SM², because this switch machine already assumes the normal straight track position. Had the switch machine SM² assumed the reverse position it would have been operated to normal in a manner as explained in the applications of S. N. Wight above referred to.

In the same manner as normal relay NR² may be caused to be energized and stuck up through a stick circuit, as just explained, the relay RR² may also be controlled. If either of these relays are energized when the lever L² is moved from the neutral position to either extreme positions the stick circuit for these relays NR² and RR² is momentarily broken so that these relays are de-energized, and this is also true if the lever

L² is moved from one extreme position to the other extreme position. It may be pointed out here that the coding keys RC², CC², and NC² are preferably operated by the lever L² through suitable time controlled mechanism, so that these 5 keys are operated at the same rate of speed regardless of the speed at which the lever L² itself is operated, this mechanism has for convenience been omitted from the drawings.

OS-ing the change in the condition of a track relay when the coding circuit is not in use

The transmission of a signal indication to a dispatcher's office to indicate the condition of occupancy of a certain track section, or other condition of traffic at a distant point, is known in railway signaling parlance as "OS-ing". Let us now consider the transmission of an OS signal from the way station at the west end of the passing siding PS¹ to the dispatcher's office. Let us assume that the train which formerly moved eastwardly in the single track section N is now entering the detector track circuit containing the track relay DT². The entrance of the train in question on this detector track circuit causes 25 the track relay DT² to assume its de-energized condition, thereby dropping its contacts 75 and 76. Dropping of contacts 75 of this relay DT² (conventionally shown by a dotted line) momentarily breaks the stick circuit for the coding stick 30 relay CSR², which stick circuit may be traced as follows:—beginning at the terminal B of the suitable battery, front contacts 75 of the detector track relay DT², wires 77 and 78, front stick contact 79 of the relay CSR², wires 80 and 81, winding 35 of the relay CSR², to the negative terminal N of this same battery. With the coding stick relay CSR² deenergized the following circuit for the lockout relay LR² is completed:—beginning at the terminal B, back contact 36 of the repeater 40 code relay RCR (located in the tower), common return wire C, wire 82, non-inductive resistance 83, wire 84, back contact 85 of the coding stick relay CSR², wire 86, winding of the lockout relay LR², wire 87, back contact 88 of the secondary 45 lockout relay SLR², wires 89, 90, back contacts 91 of the lockout relay LR¹, wire 92, winding of the secondary lockout relay SLR¹, wires 93 and LW, winding of the secondary lockout relay SLR, wire 94, back contact 95 of the lockout relay LRS, wires 50 91 and 96, back contact 37 of the repeater coding relay RCR, to the negative terminal N of the same battery. The completion of the circuit just traced energizes the lockout relay LR² and also energizes the secondary lockout relays SLR¹ and 55 SLR.

It should be noted that the energizing of the secondary lockout relay SLR¹ opens the circuit for the lockout relay LR¹, so that no code can be transmitted from the east end of the passing siding PS. Also it should be noted that the energization of the secondary lockout relay SLR prevents the dispatcher from transmitting a code from the dispatcher's office by manual operation of any one of the levers, this because the circuit over which such code would have to be transmitted is open at the back contacts 45 of the relay SLR. Also it should be noted that energization of the lockout relay LR² by attraction of its front contact 97 opens the lockout circuit for all of the secondary lockout relays, such as the secondary lockout relays SLR³, located beyond the way station containing this lockout relay LR². In other words, energization of the lockout relay LR² prevents any other transmitter beyond the 75

way station at which such lockout relay is located to function by reason of opening of the lockout circuit, and it prevents functioning of any code transmitter located between the dispatcher's office and the way station at which such lockout relay is located by reason of the energization of the normally de-energized secondary lockout circuit for that portion.

With the coding stick relay CSR² de-energized 10 and the lockout relay LR² energized the following circuit for energizing the motor M² of the code transmitter CT² is completed:—beginning at the terminal B, front contact 98 of the lockout relay LR², wires 99 and 100, back contacts 101 of the 15 coding stick relay CSR², wire 102, contact 103 of isolating cam IC², wires 104 and 105, armature of the motor M² to the negative terminal N of said battery. With this circuit completed the motor M², through suitable gearing not shown, 20 operates the coding wheel CW through a half revolution, for reasons preferably pointed out hereinafter.

As soon as the shaft of the code transmitter CT² has been operated through a comparatively small 25 angle in a clockwise direction, as indicated by the arrow, the stick contact 107 operated by the stop cam SC² through the medium of the roller 108 closes an auxiliary stick circuit for the motor M as follows:—beginning at the terminal B, contact 30 107, wires 109 and 105, armature of motor M², wire 106 to the negative terminal N. The completion of this circuit assures that the code transmitter will be operated through the rest of its 35 operating cycle, such cycle comprising a half revolution. With the code transmitter CT² operating in the direction of the arrow, shown on motor M², the coding circuit is intermittently closed to operate the master relay MR in the dispatcher's office. This coding circuit may be 40 traced as follows:—beginning at the battery 115, located in the dispatcher's office, wire 116, winding of the master relay MR, wire 117, front contacts 45 of the secondary lockout relay SLR, which relay SLR is now energized, coding wire 45 WC, wire 119, through one of the various contacts of the coding sector OC, wire 120, common return wire C, wire 121, back to the battery 115.

This intermittent completion of the circuit just traced causes the master relay MR to operate 50 in code like fashion and in turn through the following circuit affects all of the various code responsive relays CRR⁶, CRR⁸, CRR⁷, CRR⁹, etc. located in the tower:—beginning at the terminal B, wire 123, front contact 124 of the master relay MR, wire 125 through the various coding relays in multiple, wire 126, front contacts 127 of secondary lockout relay SLR, wire 128, front contacts 129 of the master relay MR, wire 130 to the negative terminal N of the same battery. With 55 the particular code transmitted by the code sector OC (signifying occupied) the code responsive selector relay CRR⁶ momentarily closes its normally open contacts 131 thereby completing the following pick-up circuit for the red indicating relay RI²:—beginning at the terminal B, contact 131 of the code responsive relay CRR⁶, wires 132 and 133, winding of the red indicating relay RI² to the negative terminal N. With the pick-up 60 circuit for the relay RI² momentarily closed this relay assumes its energized condition and closes the following stick circuit:—beginning at the terminal B, normally closed contacts 134 of the code responsive relays CRR⁸, wire 135, front stick contact 136 of the relay RI², wires 137 and 138, wind-

ing of the relay RI² to the negative terminal N. With this relay RI² energized the red lamp R² is energized through a circuit including the front contact 138 of the relay RI².

When the code transmitter CT² has almost 5 completed its coding cycle of half a revolution the following pick-up circuit for the coding stick relay CSR² is completed providing the detector track relay DT² has not in the mean time been reenergized:—beginning at the terminal B, front 10 contacts 98 of the lockout relay LR², wires 99 and 116, back contacts 116 of the detector track relay DT², wire 111, cam operated contact 112, assuming its right hand position, wires 113 and 81, winding of the coding stick relay CSR², to the 15 negative terminal N of said battery.

It should be noted if it were not for the isolating contact 103 this relay CSR² might possibly be picked up too early, and irrespective of whether or not relay LR² is up, by energy fed from B 20 through contact 107. With this pick-up circuit momentarily completed the coding stick relay CSR² is picked up, after which it is stuck up through its stick circuit heretofore traced with the contact 75 of the detector track relay DT² in 25 its retracted position. With the coding stick relay CSR² again in its energized condition the first traced circuit for the motor M² is broken at the contacts 101 of this relay CSR², and the lockout relay LR² is again de-energized because its 30 energizing circuit is broken in the contacts 85 of this relay CSR². It of course appears that with the lockout relay LR² again in its normal condition the lockout function is no longer effective and any of the other code transmitters may be 35 automatically operated to transmit a particular code to the dispatcher's office.

Let us now assume that the train in question again moves off of the detector track circuit, bearing in mind that the code transmitter has 40 only been operated through a half revolution in response to de-energization of the track relay DT². With the detector track relay DT² now moved to its attracted position the stick circuit of coding stick relay CSR² is again momentarily 45 broken, and this relay is again deenergized, thus causing the lockout relay LR² to be picked up and the code transmitter CT² to be operated through the second half of the revolution of the code transmitter CT². This operation is exactly 50 the same as that heretofore described except that the contact 112 is moved to the left instead of the right, to complete a pick-up circuit for the relay CSR² at the end of this cycle (second half revolution) and that a different and distinctive 55 code is transmitted to the dispatcher's office, which causes the code responsive relay CRR⁸ to momentarily open its contact 134 and to momentarily close its contact 134^a thereby cancelling the red lamp R² and picking up the stick relay 60 GI² and lamp G². The code for manifesting unoccupancy of the detector track section containing track relay DT² as just explained is transmitted through the coding sector UC (signifying unoccupancy) in a manner as already explained 65 in connection with coding sector OC. These two codes are distinctive as conventionally shown by the sectors OC and UC. In this connection it is desired to point out that the code responsive relay CRR⁶ and CRR⁸ are preferably such as shown 70 in the patent to Field 1,343,256 granted June 15, 1920 and may be combined into a single unit having one normally closed contact and two normally opened contacts, which contacts are actuated in response to distinctive codes.

OS-ing the change in the condition of a detector track relay when the coding circuit is in use

From the description of the operation just given it is of course apparent that the lockout relay LR^2 must be energized in order to start the code transmitter CT^2 into operation, this by reason of the fact that the motor M^2 cannot be started unless the contacts 98 of the lockout relay LR^2 are closed. Also it should be noted that when a lockout relay LR^2 is energized that the associated secondary lockout relay SLR^2 cannot be energized. Further, that with relay LR^2 energized all of the secondary lockout relays toward the dispatcher's office are in their energized condition and thereby prevent their associated lockout relays LR^1 etc. from becoming energized thereafter; and that with the lockout relay LR^2 in its energized condition, all of the lockout relays more remote from the dispatcher's office cannot be energized thereafter because the lockout circuit is broken at the back contacts 97 of the lockout relay LR^2 . In other words, it is impossible for any other lockout relay LR^1 , LR^3 , etc. to assume an energized condition if a particular lockout relay such as LR^2 , assumes its energized condition. Putting it another way, only one lockout relay can be energized at one time and for this reason only one code transmitter can be operated at one time. Not only if a particular lockout relay is energized does it lock out all of the other code transmitters, but the secondary lockout relay SLR in the tower is also energized and prevents the dispatcher from transmitting a code to a way station by operating one of his levers. In this connection attention is again directed to the indicating lamps 24 and 29 , of which the lamp 29 flickers in code-like fashion in response to manual operation of a lever and the transmission of a code, and of which the indicating lamp 24 is energized when a code is received from a distant way station for which reason the dispatcher should not operate a lever.

45 OS-ing in the event that two different track circuits are occupied or unoccupied at exactly the same instant

Let us assume, for instance, that there is an east bound train in the single track section N and that there is a west bound train in the single track section O , and that these trains pass the signals 8 and I respectively at exactly the same instant. This simultaneous occupancy of the two detector track circuits would of course cause both of the coding stick relays CSR^2 and CSR^3 to be deenergized, thereby closing their back contacts 85 and 85^3 . The closure of contact 85 of relay CSR^2 would complete an energizing circuit for the lockout relay LR^2 , and the closure of the contact 85 of the relay CSR^3 would close an energizing circuit for the lockout relay LR^3 .

Both of the relays LR^2 and LR^3 will move toward their attracted position and if the relay LR^2 should open its contact 97 before the relay SLR^2 (connected in series with relay LR^3) opens its contact 88 the relay LR^2 would prevail and the code transmitter CT^2 be operated and the transmitter CT^3 locked out. Should, however, the contact 88 of relay SLR^2 open first and contact 97 of relay LR^2 open immediately thereafter there might possibly be a bobbing back and forth between relays SLR^2 , LR^2 , SLR^3 , and LR^3 until one or the other way stations would lock out the other. In other words if two lockout relays are

energized simultaneously each of these relays will try to open the energizing circuit of the other relay. That is, the lockout relays are so interlocked that the energization of one lockout relay will result in opening the energizing circuit for the other lockout relay, and if there are a plurality of lockout relays energized simultaneously these various lockout relays will "fight", so to speak, that is will repeatedly assume the attracted and retracted position until one of these lockout relays has obtained a predominating advantage over the other lockout relay and has succeeded in opening the circuits of such other lockout relay, and may therefore remain in its energized condition. The various lockout relays and the code transmitters are so designed and have operating characteristics so that a transmitter cannot get under way while the "fight" between lockout relays continues. As soon as one of the lockout relays has won out, so to speak, its corresponding code transmitter is set into operation and causes its particular code to be transmitted.

It should be noted that the various resistance units 83 associated with the circuits for the various lockout relays become smaller in the direction from the dispatcher's office DO . The resistances of these various units are so selected that the lockout relays and secondary lockout relays will function properly regardless of the number of these relays that are connected in series, that is, regardless of the distance of the particular way station at which a lockout relay is energized. If desired, these resistance units 83 may be so selected that certain lockout relays have an advantage over other lockout relays, so that if a "fight" for the coding circuit should take place certain selected lockout relays would soon effectively lock out all other lockout relays.

Applicant has devised a circuit arrangement in which telephone selectors of commercial or special construction are co-ordinated with manually operated calling keys and automatically controlled calling keys, or code transmitters, so to enable a large number of switch machines and signals to be controlled and a large number of distinctive indications to be transmitted to the dispatcher over the same control circuit. The present invention which has been illustrated by a single embodiment whereof only, also includes a lockout circuit arrangement whereby it is impossible for more than two automatically operated code transmitters to transmit impulses over the coding circuit at a particular time. Not only does this interlocking or lockout arrangement prevent two codes being transmitted automatically simultaneously if the second code is started after the first has been partially transmitted, but the arrangement proposed does not allow the transmission of two different codes to be even started at the same time. That is, if two way stations are simultaneously conditioned to transmit distinctive codes to the dispatcher's office, both of these way station code transmitters are locked out until it has been determined which of the two shall be permitted to transmit its particular distinctive code to the way station. These features are decidedly essential and important by reason of the fact that the transmission of two codes at the same time may actually give a false indication. Also, in addition to the lockout features which prevent two codes being transmitted to the tower automatically at the same time, provision has been made to prevent the dispatcher transmitting a code if the code circuit is already in use, this being accomplished by the secondary

lockout relay, SLR located in the dispatcher's office or tower DO. Although the telephone selector or code responsive relays CRR are preferably of the construction disclosed in the Field 5 patent, above referred to, these selectors may be constructed as disclosed in the patent to Gear et al. No. 1,118,120 dated Nov. 24, 1914.

Having thus shown only one rather specific embodiment of my invention, it should be understood that this has been done for the purpose of facilitating the illustration and description thereof, and the particular embodiment shown and described has not been selected for the purpose of illustrating the scope of the invention or the 10 exact construction preferably employed in practicing the invention, and it is to be understood that various changes, modifications, and additions may be made to adapt the invention to the particular installation and track layout to which 15 the invention is to be applied, all without departing from the spirit and scope of the invention and the idea of means underlying the same except as demanded by the scope of the appended claims.

What I claim is:—

25 1. A train dispatching system of the type in which information is transmitted to the engineer of a moving train by distinctive codes transmitted from a dispatcher's office and in which indications are transmitted to the dispatcher's 30 office comprising, code-responsive means in the dispatcher's office closing one contact and opening another contact upon the reception of a particular code, and closing a third contact and opening a fourth contact upon the reception of another distinctive code, two stick relays associated with said code-responsive means one of which is picked up in response to momentary closure of said one contact and which has its stick circuit opened upon and only upon the 35 opening of said fourth contact and the other of said stick relays of which has its pick-up circuit closed upon closure of the third contact and has its stick circuit broken upon and only upon the opening of said another contact, and code-transmitting means located at a distant way station for transmitting such particular code and such another distinctive code.

2. A train dispatching system of the type in which information is transmitted to the engineer 50 of a moving train by distinctive codes transmitted from a dispatcher's office and in which indications are automatically transmitted to the dispatcher's office comprising, code-responsive means in the dispatcher's office momentarily closing one contact and opening another contact upon the reception of a particular code, and closing a third contact and opening a fourth contact upon the reception of another distinctive code, two stick 55 relays associated with said code-responsive means one of which is picked up in response to momentary closure of said one contact and which has its stick circuit opened upon and only upon the opening of said fourth contact, and the other of said stick relays has its pick-up circuit closed upon closure of said third contact and has its stick circuit broken upon and only upon the opening of said another contact, indicating means in the dispatcher's office controlled by said stick 60 relays, and means at a distant way station for transmitting such particular code and such another distinctive code to the dispatcher's office.

3. An automatically-operated code transmitter for indicating the condition of a relay controlled 65 in accordance with traffic conditions; a normally

energized stick relay for controlling said code transmitter; and means including such stick relay for operating said code transmitter through a half cycle if said traffic controlled relay is changed from one condition to another condition, 5 and operating said code transmitter through an entire cycle if said traffic controlled relay is changed from one condition to another and then is immediately changed back to said one condition. 10

4. In a dispatching system of the code-responsive type, the combination with a dispatcher's office and a plurality of way stations, a single line circuit connecting said dispatcher's office with all of said way stations, code-responsive selector means at each way station each distinctively responsive to a particular code transmitted from the dispatcher's office, and a lever in the dispatcher's office having code transmitting means associated therewith, which will transmit one particular code when moved from an intermediate position to an extreme position, will transmit another particular code when moved from an intermediate position to another extreme position, will transmit no code when moved from either extreme position to the corresponding respective intermediate position, and will transmit a third distinctive code when moved from one to the other of said intermediate positions, said particular codes being capable of operating certain 30 of said code-responsive devices. 25

5. In combination, a distant way station, a local office, a traffic controlling device at said way station, apparatus comprising code creating and code responsive apparatus for transmitting to said office a change in the condition of said traffic controlling device, a change storing relay normally assuming a certain condition which if changed manifests that an indication of a change of said traffic controlling device must be transmitted to said office, means for actuating said change storing relay upon a change in said traffic controlling device, a contact reflecting the condition of said traffic controlling device, another contact reflecting the last code transmitted to said office, and means for preventing said change storing relay being returned to normal until said contact and said another contact assume corresponding positions. 35

6. In combination, a distant way station, a local office, a traffic controlling device at said way station, apparatus comprising code creating and code responsive apparatus for transmitting to said office a change in the condition of said traffic controlling device, a change storing relay normally assuming a certain condition which if changed initiates said apparatus to transmit an indication of a change of said traffic controlling device to said office, means for actuating said change storing relay upon a change in said traffic controlling device, a contact reflecting the condition of said traffic controlling device, another contact reflecting the last code transmitted to said office, and means to maintain said apparatus in operation to transmit a cancelling code, 60 in the event said traffic controlling device is changed to a new condition and is then returned to its previous condition before an indication of said new condition was transmitted, including a circuit manifesting the condition of correspondence of said contact and said another contact. 65

7. In combination, a local office, a distant station, a normally energized track relay which when deenergized manifests the presence of a train in a track section, selector apparatus for transmit- 70 75

- ting by an occupied or unoccupied code the condition of said track relay, a change storing relay normally assuming a certain condition which if changed initiates said apparatus into operation 5 and which is changed when said track relay assumes a new condition, and means manifesting at said station the last of said two codes which was transmitted by said apparatus for returning said change storing relay to normal.
- 10 8. A train dispatching system of the type in which the information is transmitted to the engineer of a moving train by distinctive codes transmitted from a dispatcher's office and in which indications are automatically transmitted to the 10 dispatcher's office comprising, code-responsive means in the dispatcher's office closing one contact and opening another contact upon the reception of a particular code, and closing a third contact and opening a fourth contact upon the 15 reception of another distinctive code, two stick relays associated with said code-responsive means one of which is picked up in response to momentary closure of said one contact and which has its stick circuit opened upon the opening of said 20 fourth contact, and the other of said stick relays has its pick-up circuit closed upon closure of said third contact and has its stick circuit broken upon the opening of said another contact, indicating means in the dispatcher's office controlled 25 by said stick relays, and means at a distant way station for transmitting such particular code and such another distinctive code to the dispatcher's 30 office.
9. A train dispatching system of the type in which the information is transmitted to the engineer of a moving train by distinctive codes transmitted from a dispatcher's office comprising, code-responsive means closing one contact and opening another contact upon the reception 35 of a particular code, and closing a third contact and opening a fourth contact upon the reception of another distinctive code, two stick relays associated with said code-responsive means one of which is picked up in response to momentary 40 closure of said one contact and which has its stick circuit opened upon the opening of said fourth contact and the other of said stick relays has its pick-up circuit closed upon closure of the third contact and has its stick circuit broken 45 upon the opening of said another contact, and code-transmitting means located at a distant point for transmitting such particular code and such another distinctive code.
10. A train dispatching system of the type in which the information is transmitted to the engineer of a moving train by distinctive codes transmitted from a dispatcher's office comprising, code-responsive means closing one contact and opening another contact upon the reception 50 of a particular code, and closing a third contact and opening a fourth contact upon the reception of another distinctive code, two stick relays associated with said code-responsive means one of which is picked up in response to momentary 55 closure of said one contact and which has its stick circuit opened upon the opening of said fourth contact, and the other of said stick relays has its pick-up circuit closed upon closure of said third contact and has its stick circuit broken upon the opening of said another contact, indicating means controlled by said stick relays, and means at a distant point for transmitting such particular code and such another distinctive code.
11. In a centralized traffic controlling system 75 of the code, the combination with a central office and a plurality of field stations, of code transmitting means for transmitting through the medium of distinctive codes conditions of traffic from a distant field station to said central office, a stick relay at such field station, means for picking up said stick relay only upon the transmission from such field station to said central office of a multiple impulse code identifying the condition of traffic then existing, means for dropping said stick relay upon a change of traffic conditions at such field station, and a circuit for controlling said code transmitting means controlled by said stick relay.
12. In a centralized traffic controlling system 15 of the code type; the combination with a central office and a plurality of field stations; of code transmitting means for transmitting through the medium of distinctive codes, each comprising a plurality of impulses, conditions of traffic from a distant field station to said central office; a contact reflecting traffic conditions at each field station; a normally energized starting relay at each field station having a stick circuit including said contact for that station and momentarily broken when said contact is moved from one traffic reflecting condition to another traffic reflecting condition; a circuit for initiating said code transmitting means controlled by said starting relay; and a pick-up circuit for said starting relay closed only when said code transmitting means has transmitted a code corresponding to the position then assumed by said contact.
13. In a centralized traffic controlling system 35 of the code type; the combination with a central office and a plurality of field stations; of code transmitting means for transmitting through the medium of distinctive codes, each comprising a plurality of impulses, conditions of traffic from a distant field station to said central office; a contact reflecting traffic conditions at each field station; a normally energized starting relay at each field station having a stick circuit including said contact for that station and momentarily broken when said contact is moved from one traffic reflecting condition to another traffic reflecting condition; a circuit for initiating said code transmitting means controlled by said starting relay; a second circuit for continuing operation of said code transmitting means closed upon initiation of said code transmitting means and opened when a complete code has been transmitted; and a pick-up circuit for said starting relay closed during operation of said 40 code transmitting means only if the code transmitted corresponds to the position then assumed by said contact.
14. In a centralized railway traffic controlling system of the code type, the combination with a central office and a plurality of field stations, a circuit including a line wire and a common wire extending from said office to the first field station and from station to station, code transmitting means at each of said field stations for transmitting to said office a series of impulses characterizing a code, a second line wire extending from said office to said first station and from station to station, a railway traffic device reflecting at each station the condition of traffic which 50 is to be indicated, a first relay at each station changed from one condition to another upon a change in the condition of said device for that station and changed only from said another to said one condition upon transmission of a code 55
- 75 11. In a centralized traffic controlling system of the code, the combination with a central office and a plurality of field stations, of code transmitting means for transmitting through the medium of distinctive codes conditions of traffic from a distant field station to said central office, a stick relay at such field station, means for picking up said stick relay only upon the transmission from such field station to said central office of a multiple impulse code identifying the condition of traffic then existing, means for dropping said stick relay upon a change of traffic conditions at such field station, and a circuit for controlling said code transmitting means controlled by said stick relay.

by the associated code transmitting means, a second relay which if energized disconnects said second line wire from more remote stations and energized from a source at said office and over said second line wire when said first relay assumes said another condition, and a circuit for rendering said code transmitting means active controlled by said second relay.

15. In a centralized railway traffic controlling system of the code type, the combination with a central office and a plurality of field stations, a circuit including a line wire and a common wire extending from said office to the first field station and from station to station, code transmitting means at each of said field stations for transmitting to said office a series of impulses characterizing a code, a second line wire extending from said office to said first station and from station to station, a railway traffic device reflecting at each station the condition of traffic which is to be indicated, a stick relay at each station having a stick circuit including a contact momentarily opened upon a change in the condition of said device for that station and having a pick-up circuit closed upon transmission of a code by the associated code transmitting means, a second relay which if energized disconnects said second line wire from more remote sta-

tions and energized from a source at said office and over said second line wire when said first relay assumes its deenergized condition, and a circuit for rendering said code transmitting means active controlled by said second relay. 5

16. In a centralized traffic controlling system of the code type, the combination with a central office and a field station; of code transmitting means at said field station for transmitting through the medium of distinctive codes, each comprising a plurality of impulses, conditions of traffic from said field station to said office; a track relay at said field station; a normally energized stick relay at said field station having a stick circuit including front and back contacts of said track relay in multiple, whereby a change in the condition of said track relay de-energizes said stick relay; a circuit for initiating said code transmitting means controlled by said stick relay to cause said code transmitting means to transmit a code corresponding to the condition then assumed by said track relay; and a pick-up circuit for said stick relay closed only when said code transmitting means has transmitted a code corresponding to the condition 10 15 20 25 then assumed by said track relay. 25
